Chas. G. Wells, of Philadelphia, Penn.

Assign to

W. H. Swift and Henry B. Courtney of Wilmington, Del.
Letters Patent No. 1805. Dated July 2nd 1863.

The schedule referred to in these Letters Patent and making part of the same.

To all whom it may concern:

Be it known that I, G. G. Wells, of Philadelphia, County of Philadelphia, State of Pennsylvania have invented or produced a new and original design for a Label, and I do hereby declare the accompanying drawing, with the following explanation of the same, to form a full, clear and exact description of the said design.

The label is edged with a plain border and has a simple ornament at each of the four corners.

Near the upper edge of the label are the words "Diamond State," each letter of the said words being contained in a separate panel of the form represented in the drawing.

Below the words "Diamond State" are the words "Parlor Match," each of which is contained in a lozenge shaped panel, the two panels being connected together by a lozenge shaped ornament, and being ornamented with the sprigs shown.

Near the lower edge of the label are the words "Manufactured by Swift and Courtney, Wilmington,

"Delaware," and between the words "Diamond Plate" and the words "Parlor Match" are arranged the words "Superior to any match in the American market."

I claim the figures and forms represented in and by the accompanying drawing, the whole forming an ornamental design for a label.

In testimony whereof I have signed my name to this specification in the presence of two subscribing witnesses.

Witnesses:

Henry Cowson,

E.G.S. John White.)
